CLAIM

The ornamental design for a shank for a handle tool, as shown and described.

DESCRIPTION

FIG. 1 is a perspective view of a shank for a handle tool showing my new design, the broken-line showing of the handle and shovel blade is for illustrative purposes only, and forms no part of the claimed design;

FIG. 2 is a front elevation thereof;

FIG. 3 is a rear elevation thereof;

FIG. 4 is a side elevation thereof;

FIG. 5 is an opposite side elevation thereof;

FIG. 6 is a top plan view thereof;

FIG. 7 is a bottom plan view thereof; and

FIG. 8 is a horizontal cross-sectional view thereof, taken along line 8—8 in FIG. 1.
